STRUCTURAL MEMBER AND METHOD OF
MAKING SAME

Clarence H. Moore and James G. Moore, Jacksonville, Fla., assignors to The Aetna Iron & Steel Co., Jacksonville, Fla., a corporation of Florida

Application December 1, 1938, Serial No. 243,427

8 Claims. (Cl. 29—155)

This invention relates to metal structural members, such as flanged girders and beams, and to the method of making the same. A principal purpose of the invention is to provide such structural members reinforced in a novel manner whereby their strength is greatly increased.

Heretofore, it has been a common practice to weld superposed reinforcing strips or plates along the outer faces of girder flanges. Maximum efficiency is, however, not obtained by this system, since stresses are still transmitted between the flange and web only through the single joint existing between the two. According to the present invention, superposed reinforcing strips, plates or bars, ordinarily of rectangular form, are applied to the inner face or faces of the flange with certain of the strips in actual longitudinal abutment with the web and directly welded thereto so that stresses are transmitted between the flange and web through such joints, as well as through the direct joint between the flange and web.

The invention is exemplified in the accompanying drawing to which reference will be made in the following description.

In the drawing:

Figure 1 is a side elevation of a structural member, here a plate girder, embodying the invention;

Figure 2 is an enlarged section substantially on line 2—2 of Figure 1;

Figure 3 is a section similar to that of Figure 2 but of a modified construction;

Figure 4 is a section similar to that of Figure 2 but of a further modified construction;

Figure 5 is a section substantially on line 5—5 of Figure 4;

Figure 6 is a side elevation of a structural member, here an I-beam with integral web and flanges, embodying the invention;

Figure 7 is a section substantially on line 7—7 of Figure 6;

Figure 8 is a section substantially on line 8—8 of Figure 6, and

Figure 9 is a section substantially on line 9—9 of Figure 8.

Referring first to Figures 1 and 2, the metal girder generally designated at 10 has a web 11 and top and bottom flange plates 12 and 13, each of which projects on both sides of the web to give an I section. The flange plate 12 is here considered to be welded to the web 13, the weld fillets appearing at 14, Figure 2. Applied flatwise to the inner faces of the flange plate 12 are metal strips, plates or bars 15 and 16. The inner rectilinear edges of these strips are spaced from

web 13 to provide clearance for the weld fillets 14 and also for the weld fillets 17 and 18, which are formed between the adjacent edges of the strips and the flange plate. The outer edges of strips 15 and 16 are spaced inwardly of the outer edges of plate 12 and united with the latter through the weld fillets 19 and 20. According to the invention, the flange plate and web may first be welded together and then the strips 15 and 16 applied, or the strips may be first applied to the flange plate and then the web welded to the latter. The result is the same in both cases, either procedure being readily carried out, due to the spaces which are provided, and in which either sequence of welding operations is readily carried out. Edges 17 and 18, as here shown, are the ordinary square edges; i. e., perpendicular to the strip faces.

Strips 21 and 22 are imposed flatwise on strips 15 and 16 with their rectilinear inner square edges 23 and 24 throughout against web 13 and secured to the latter through the weld fillets 25 and 26. Strips 15 and 16 overhang the outer edges of strips 21 and 22 and are joined with the latter by the welds 27 and 28.

The invention is exemplified in the structure thus far described, since plates 21 and 22 are directly welded to the web 13 in stress transmitting relation. The strips or plates may be of any suitable length, but preferably strips 15 and 16 are somewhat shorter than the flange plate 12 and strips 21 and 22 are somewhat shorter than the strips 15 and 16, as indicated in Figure 1. The weld fillets are ordinarily intermittent but may be coextensive with the respective strips and extend across the ends of the latter.

If desired, further strips 29 and 30 may be applied flatwise to strips 21 and 22 and welded to the latter, the inner edges of strips 29 and 30 being spaced from web 13 to provide clearance for the weld fillets. Plates 31 and 32 may be imposed on plates 29 and 30 in the manner shown, the adjacent edges of strips 31 and 32 abutting web 13 and being welded thereto, while the outer portions of the strips are welded to strips 29 and 30. It is obvious that further strips may be applied in the described manner, if desired. As indicated in Figure 1, the lower flange 13 may be reinforced in exactly the same manner as just described in connection with the first flange. Four strips 33, 34, 35 and 36 are shown, these corresponding with strips 15, 21, 29 and 31, and being preferably duplicated on the other side of the web.

In Figure 3, the general arrangement is the

same as that described in connection with Figures 1 and 2. In this case, however, the applied plates instead of diminishing in width away from the flange, are of such width that strips 37, 38, 5 39 and 40 project laterally beyond the edges of flange 41 while the strips 42, 43, 44 and 45 terminate laterally in the planes of the flange edges, the weld fillets being formed as shown. This 10 construction is very satisfactory in use, but less convenient in production than that of Figures 1 and 2. In the latter figures, the welds are all formed on the lower sides of the various plates, whereas in Figure 3 plate 31, for example, is united with plate 41 by a top weld at its outer portion and by a bottom weld with plate 41 at its inner portion, and so on.

The arrangement shown in Figure 4 corresponds generally with that of the previously described figures. In this case, however, the outer edges of the plates lie in the same planes, and grooves are formed between the plates to receive the weld fillets as at 46. As shown in Figure 5, the ends of space 47 may be plugged as at 48, and the plug may be a weld plug or of a plastic 25 waterproof composition of any suitable formula. On the other hand, the entire space 47 outside of that occupied by the weld fillets may be filled with a suitable plastic waterproof composition. It will be understood that all the spaces in all 30 embodiments may be treated in this manner.

In Figures 6 to 9, the beam 49 is of I-section and includes a web 50 and top and bottom flanges 51 and 52 integral therewith. The top flange has the sets of plates 53, 54; 55, 56; and 57, 58 applied thereto. The strips may be applied in the manner heretofore described, or as an alternative, and as indicated, the strips 53, 55 and 57, for example, may be first welded together and then applied as a unit to the beam by welding plate 40 53 to flange 51 along the line 59, and plate 55 to web 50 along the line 60, or plates 53 and 55 may be applied to the beam as a unit and then plate 57 applied. If desired, further strips, abutting and welded to web 50 may be applied to strips 57 45 and 58, and so on.

It will be seen that in all cases the weld fillet between the first applied plate and the flange and adjacent the web, as at 17, Figure 2, or between the first and second plates, as in Figure 8, is confined to a disposition between the inner face of the flange and the plane of the outer face of the first plate, i. e., the plane of that face of the first plate which is remote from the flange.

It will be understood that the invention is by 55 no means limited to the form and arrangement of parts shown except in the essentials pointed out in the following claims.

We claim:

1. A metal structural member including a web 60 and a flange, and reinforcing means comprising a plate in contact with the inner face of said flange and having an outer edge extending along and adjacent the outer edge of said flange and welded to said flange and an inner edge extending along said flange and spaced from said web 65 sufficiently to accommodate a weld fillet confined to a disposition between said inner face of the flange and the plane of the outer face of said plate, and a second plate imposed on the first and having an inner edge lying against said web and 70 welded thereto, said second plate having an outer edge adjacent the outer edge of the first plate and welded to the first plate.

2. A structural member according to claim 1

wherein the first plate is welded to the web in the space existing between the latter and the inner edge of said first plate.

3. A structural member according to claim 1 wherein the first plate is welded to the second 5 in the space existing between the inner edge of the first plate and the web.

4. A structural member according to claim 1 wherein the ends of the space which exists between the inner edge of the first plate and web 10 are plugged.

5. A structural member according to claim 1 wherein such of the space between the inner edge of the first plate and the web as is not filled by a weld fillet is filled with a plastic waterproof material.

6. The method of reinforcing a metal structural member, said member comprising a flange and a web, said method comprising applying a metal plate to the inner face of said flange with 20 the inner edge of said plate in spaced relation to said web and the outer edge of said plate adjacent the outer edge of said flange, welding said edge to said flange within the space existing by reason of said spaced relation, the weld being confined to a disposition between said inner face of the flange and the plane of the outer face of said plate, welding the outer edge of said plate to said flange, applying a second metal plate to the exposed face of the first with the inner edge of 30 the second plate abutting said web and its outer edge adjacent the outer edge of the first plate, and welding said abutting edge to said web and the outer edge of said second plate to the first plate.

7. The method of reinforcing a metal structural member, said member comprising a flange and a web, said method comprising imposing one metal strip flatwise on another with one edge of the one spaced in parallel relation from an 40 edge of the other so that a marginal portion of said other is exposed between said edges and with the opposite edges of said strips adjacent each other, forming a weld fillet in the angle between said marginal portion and the adjacent edge of 45 said one strip, applying the thus formed unit to said structural member with the exposed face of said one strip against said flange and the edge of said other strip which is adjacent said fillet against said web, and welding the last named 50 edge to said web and the outer edge of said unit, which is adjacent the outer edge of said flange, to said flange.

8. The method of making a reinforced metal structural member which comprises welding a 55 pair of strips in parallel spaced relation and flatwise along one face of a plate so that weld fillets are formed between the adjacent edges of the strips and the plate, welding the outer edges of 60 said strips, which are adjacent the outer edges of said plate, to said plate, disposing a second plate on edge against the first and between said adjacent edges in spaced relation to the latter, welding the two plates together in flange and web relation, applying a second pair of strips on 65 the first with the adjacent edges of said second pair in abutment with said second plate and with their outer edges adjacent the outer edges of the first pair of strips, and welding said abutting edges of said second pair to said second plate and the outer portions of said second pair to the first 70 pair of strips.
